UNITED STATES PATENT OFFICE.

SIGMUND HERBERT, OF NEW YORK, N. Y.

DESIGN FOR A HOLDER FOR VASES OR SIMILAR ARTICLES.

Application filed April 19, 1923. Serial No. 5,854. Term of patent 3½ years.

To all whom it may concern:

Be it known that I, SIGMUND HERBERT, a citizen of the United States of America, residing in the borough of Manhattan, city, county, and State of New York, have invented a new, original, and ornamental Design for a Holder for Vases or Similar Articles, of which the following is a specification, reference being had to the accompanying drawing, forming a part thereof,

The figure is a perspective view of the design for a holder for vases or similar articles.

I claim:

The ornamental design for a holder for vases or similar articles, substantially as shown.

SIGMUND HERBERT.
